Primary Examiner — Cathron C Brooks*Assistant Examiner* — Sharon S Oum**CLAIM**

An ornamental design for a fan grate, as shown and featured in the accompanying drawings.

DESCRIPTION

FIG. 1 is a left, front, top perspective view of a fan grate in accordance with the present invention;

FIG. 2 is a top view thereof;

FIG. 3 is a bottom view thereof;

FIG. 4 is a front elevation view thereof;

FIG. 5 is a back elevation view thereof;

FIG. 6 is a left elevation view thereof;

FIG. 7 is a right elevation view thereof; and,

FIG. 8 is a left, front, top perspective view thereof as used within an example fan.

The broken lines in FIG. 8 illustrate environmental structure of the fan grate and form no part of the claimed design.
